WRENCH

William B. Lucas, New York, N. Y., assignor of
one-half to Peter L. Wilbur, Tuckahoe, N. Y.

Application August 21, 1933, Serial No. 686,000

2 Claims. (C.I. 81—99)

This invention relates to wrenches adapted for the application of nuts to bolts and the like or to serve as a pipe wrench, embodying a lever in the form of a bar one end of which is adapted to serve as a hand grip and the opposite end as a gripping jaw, and a second lever arranged with a jaw pivotally connected to the jaw end of the first lever, the jaw of the second lever being adapted to have angular adjustment relative to the jaw end of the first lever to permit of the application of the wrench to different sizes of nuts or pipes and the like. In the commercial type of wrench of this character the movable lever has a fixed pivotal connection with the other lever, and as the jaws are adapted to only grip nuts coming within a predetermined size it is necessary to have several sizes of wrenches. In the use of the wrench as a pipe wrench it is necessary that the jaws be serrated in order that the jaws shall grip the round surface of the pipe, and as the jaws of a wrench are adapted to be utilized only with pipe coming within a predetermined diameter, it is not only necessary to have a separate wrench for use as a pipe wrench but also several sizes of such wrenches for different sizes of pipes.

It is the primary object of the invention to provide a wrench of this character wherein the pivoted lever has a releasable connection with the lever arranged with the hand grip and thus adapting one lever for the interchangeable connection of different sizes of pivoted levers, and thus adapt the same for use in connection with different sizes of nuts or pipes and thus greatly reduce the cost to the user of such wrenches.

In wrenches of this character heretofore the jaws have been arranged so that the stress on the jaws in the gripping of a nut or pipe are exerted as a bending stress on the outer ends of the jaws and tending to rupture the same. It is a further object of the invention to provide an improved construction and arrangement of jaws in wrenches of this character whereby the stresses of the gripping force on the movable jaw will be in a direction inward from the end, and on the other jaw in a direction toward the axis of the pivotal connection of the levers and thus relieving the jaws of any bending and rupturing stresses.

In the drawing accompanying and forming a part of this application Figure 1 is a front elevation of my improved wrench showing the jaws in normal position.

Figure 2 is a side elevation of the upper portion of the wrench looking at the right of Figure 1.

Figure 3 is a front elevation of the upper por-

tion of the wrench with one lever partly in section to show the pivotal connection of the levers and showing in dotted lines the different positions to which the pivoted lever is adjustable for the application of the same to nuts or pipes of different sizes.

Figure 4 is a perspective view of the jaw end of one of the levers to show the arrangement thereof for the pivotal connection of the other lever thereto.

Figure 5 is a front elevation of the pivoted jaw.

Figure 6 is a side elevation of the pivoted jaw looking at the right of Figure 5.

Figure 7 is a front elevation of the pivoted jaw showing a modified structure thereof to adapt it as a pipe gripping jaw.

Figure 8 is a front elevation of the jaw end of the wrench showing in a diagrammatic manner the gripping of a nut or pipe between the jaws and the direction of the stresses on the jaws during the gripping action.

In the embodiment of the invention illustrated in the drawing the one lever 9 is in the form of a bar arranged as a hand grip at one end and bent adjacent one end laterally in the direction of its width, as at 10, and then bent in a reversed direction, as at 11, to provide a jaw 12 at the end of the lever the opposite edges 13, 14 of which extend in parallel relation at an acute angle to the longitudinal axis of the lever with the jaw face 15 arranged at the end, said face being of eccentric or irregular arcuate form the curvature of which extends transversely of the width of the lever and downwardly from an edge thereof, in the present instance the edge 13, to the opposite edge 14. A slot 16 is extended transversely through the width of the lever 9 and extending from the end of the jaw 12 at the bend 11 toward the opposite end of the lever. The end wall of the slot opposite to the jaw face 15 has a portion 17 extending at a right angle to the edges 13, 14 of the jaw, and a portion 18 extending at an acute angle thereto with an arcuate recess 19 interposed between said wall portions, said recess being of arcuate shape in cross section, as shown at 20.

The other lever is substantially of arcuate shape in longitudinal section arranged with a jaw 21 at one end and a shank portion 22 extending from substantially midway the length thereof to the opposite end, the shank being of less thickness than the jaw end and of a thickness to loosely engage in the lever slot 16. The end portion 23 of the face of the jaw extends inwardly from the end in angular relation to the adjacent portion 24 of the jaw face, and the lever is pivotally and

removably connected with the other lever with the jaw face in opposed relation to the lever jaw 12 by a circular ear 25 extended inwardly from adjacent the end of the shank 22 in opposed relation to the jaw face, said ear being adapted to pivotally engage in the arcuate recess 19 in the end wall of the slot 16, and the edge thereof being of arcuate shape in cross section, as shown at 25', to correspond with the cross sectional curvature 20 of the recess 19, whereby the jaw end 21 of the lever may have slight lateral canting movement to compensate for irregularities in a nut or pipe engaged between the jaws. By this arrangement of the pivotal connection of the levers the 15 lever jaw 21 will be in overhanging relation to the lever jaw 12, and is normally yieldingly urged to maintain the pivotal connection and to the position shown in Figure 1 by a leaf spring 26 fixed at one end by suitable means, as by a rivet 20 27, to the lever 9, the free end being arranged to extend into the lever slot 16 and engage the outer surface of the lever shank 22 at one side of the center of the pivot ear 25, and thereby by the inherent tension thereof urge the jaw end 21 of the 25 pivoted lever in a direction toward the lever jaw 12. The outer arcuate face of the shank end of the pivoted lever is eccentric to the axis of the pivot ear 25 and by this arrangement the end portion of the spring 26 will engage the pivoted lever in all positions thereof at the side of the pivot ear 25, as shown in dotted lines in Figure 3. To facilitate the moving of the jaw end of the pivoted lever away from the jaw 12 against the tension of spring 26 for the engagement of nuts 30 or pipes of different sizes between the jaws, said lever is provided with a finger or thumb engaging projection 28 extending laterally from the pivot end thereof and in all positions of the lever projecting from the lever slot 16.

40 As stated, a pivoted lever in a wrench of this type is adapted for application of nuts within certain limits, and to use the same with nuts of larger size the pivoted jaw must be of larger size. Also to utilize the same as a pipe wrench in order 45 to effectively grip the pipe it is necessary that the face portion 23 of the pivoted jaw be provided with a gripping surface, usually provided by transversely serrating said portion of the jaw face 23, as shown at 23' in Figure 7, and by the pivotal connection of the levers as described the pivoted lever is interchangeably connected with the lever 9 and in order that the pivoted lever may be readily removed and another substituted therefor by exerting a downward force on said lever against 50 the tension of the spring 26 to disengage the pivot ear 25 from the recess 19, and then moving the lever laterally out of the lever slot 16, and it may be as readily connected with the lever 9 by inserting the shank 22 of the lever in the lever slot 16 against the tension of the spring and then move it upward to engage the pivot ear 25 in the recess 19.

55 By the arrangement of the lever jaws described the jaw of the pivoted lever is adapted to have angular adjustment relative to the jaw of the other lever and thus adapt the wrench for use in connection with sizes of nuts, as shown at 30 in full lines in Figure 3, and a pipe or rod having a corresponding diameter, and up to a size of nut, 60 as shown in dotted lines 30' in Figure 3, or a pipe or rod of a corresponding diameter, and for use in connection with nuts or pipes of larger size a pivoted lever may be readily substituted to adapt the wrench for use in connection with such nuts 65 of larger size.

Furthermore, by the arrangement of the face 23, 24 of the pivoted lever relative to the pivot ear 25 and the arrangement of the lever jaw 12 and its face 15 the force of the stresses of the jaw 12 are transmitted to the jaw 21 in a direction inward 5 from the end of the face 23 on a line 31 (Figure 8) extending at approximately 27 degrees to a line 32 extended through the center of the pivotal connection of the levers and the corner formed at the juncture of the angular portions 23, 24 of the 10 face of jaw 21. The angular portions 23, 24 of the jaw face are arranged to conform to a nut of square or hexagonal form, in the present instance shown for use with hexagonal nuts, so that said faces will embrace the adjacent faces of the 15 nut and hold the nut or pipe to the jaw 12 by a force exerted on the line 32, and the stress of the force of drawing a nut or pipe home, which is in a direction indicated by the arrow a, is transmitted through the jaw 12 to the jaw 21 substantially in a direction indicated by the line 31, the face 15 of jaw 12 due to the irregular or eccentric curvature thereof engaging the nut at a point within a corner thereof.

Instead of providing the pivoted lever with the 25 finger or thumb grip 28, the end adjacent the pivot ear and normally projecting from the lever slot 16 may be serrated as shown at 28' in Figure 7.

Having thus described my invention I claim:

1. In a wrench, a lever arranged as a hand grip with a jaw at one end having an arcuate curved end face the curvature of which extends from one side downwardly to the opposite side and said lever having a slot extended therethrough in the direction of the face of the jaw with an arcuate recess in the end wall opposed to the jaw face to adapt the same for the interchangeable pivotal connection of one of a series of levers thereto, each of said interchangeable levers being of arcuate 40 shape in longitudinal section with the inner edge arranged as a series of straight line portions extending at an angle to each other, a pair of straight line portions at one end constituting an angular jaw face and the opposite end of said lever being adapted to engage in the slot of the first lever and having a circular ear extended inwardly therefrom in parallel relation to a straight line portion adjacent the jaw face and adapted to engage the arcuate recess in the end wall of the lever slot to pivotally connect the levers with said straight line portion adjacent the jaw face in opposed relation to a side of the jaw of the first lever, said faces of the lever jaws being arranged whereby the force of the stress of the jaw of the first lever on an article between the jaws is transmitted through the jaw to the pivoted lever in a line extended at an acute angle to a line extended through the center of the pivotal connection of the levers and the corner formed by the outer angular portions of the face of the jaw of the second lever, and means to yieldingly maintain the levers pivotally connected and urge the straight line portion adjacent the jaw face of the second lever to abut the opposed side of the jaw of the first lever.

2. In a wrench, a lever having a jaw at one end the face of which is of eccentric arcuate form the curvature of which extends transversely of the width of the lever and downwardly from one edge to the opposite edge of the lever, said lever having a slot extended therethrough transversely of the width adjacent the jaw end and having an arcuate recess in the wall opposed to the jaw face, and 75

a second lever of arcuate form in longitudinal section having a shank at one end to engage in the lever slot and having a circular ear extended inward from adjacent the shank end adapted to engage the arcuate recess in the wall of the lever slot to pivotally connect said lever with the first lever, and the other end of the second lever arranged as a jaw to overhang the face of the first

lever and have adjustment angularly thereof to vary the space between the jaws, the cross section of the arcuate recess and circular ear being of corresponding arcuate form to permit of limited lateral movement of the lever jaws relative to each other to compensate for irregularities in articles engaged between the jaws. 5
